UNITED STATES PATENT OFFICE.

GEORGE G. GAREY, OF INDIANAPOLIS, INDIANA.

WATER-RESERVOIR ATTACHMENT FOR STOVES AND RANGES.

1,115,063.

Specification of Letters Patent. Patented Oct. 27, 1914.

Application filed June 25, 1913. Serial No. 775,822.

To all whom it may concern:

Be it known that I, GEORGE G. GAREY, a citizen of the United States, residing at Indianapolis, in the county of Marion and 5 State of Indiana, have invented a new and useful Water-Reservoir Attachment for Stoves and Ranges, of which the following is a specification.

This invention relates to a water reservoir 10 for cooking ranges and stoves, one of its objects being to provide a device of this character which can be quickly placed in or removed from position and which is so shaped as to present the maximum area of 15 heating surface to the heated wall of the range or stove so that the contents of the reservoir will be quickly heated to a high temperature.

A further object is to provide improved 20 means for binding one wall of the reservoir against the corresponding wall of the range or stove, said holding means being also adapted to hold the wall of the reservoir out 25 of contact with the range or stove when it is desired to reduce the transmission of heat units to the contents of the reservoir.

With the foregoing and other objects in view which will appear as the description proceeds, the invention resides in the combination and arrangement of parts and in the details of construction hereinafter described and claimed, it being understood that changes in the precise embodiment of the invention herein disclosed, can be made within 35 the scope of what is claimed, without departing from the spirit of the invention.

In the accompanying drawings the preferred forms of the invention have been shown.

40 In said drawings:—Figure 1 is a vertical transverse section through the reservoir and the adjoining portion of the range to which it is applied. Fig. 2 is a side elevation of the reservoir and range, a portion of the 45 reservoir being broken away. Fig. 3 is a section on line A—B Fig. 1. Fig. 4 is a view similar to Fig. 1 but showing the reservoir shifted outwardly away from the wall of the range. Fig. 5 is a section on line 50 C—D Fig. 1. Fig. 6 is a horizontal section through a portion of the reservoir and the coacting face of a range or stove, the same being a slightly modified form. Fig. 7 is a view similar to Fig. 6, showing another 55 modified form.

Referring to the figures by characters of

reference 1 designates a portion of a range or other form of stove and, in the structure shown in Figs. 1 to 4 inclusive, one wall of this range has vertical corrugations 2 outstanding therefrom, the upper ends of which are finished in any suitable manner, as by means of a ledge 3 closing the spaces defined by the corrugations. The lower ends of the corrugations can also be finished in 60 any preferred manner and in the structure shown the said lower ends are closed and the outermost portions of the corrugations are flush with that portion 4 of the stove wall below the corrugations, said portion 65 being straight from one side to the other of the wall. Openings 5 may be provided in the upper portion of the wall at points above the corrugations 2 for the purpose hereinafter set forth. Furthermore slotted 70 and recessed lugs 6 or other suitable connecting means may be formed on or secured to the stove wall at points below the corrugations.

The reservoir to be used in connection 80 with the stove having the corrugated wall has its walls and bottom preferably formed of sheet metal, the front, back and outer side walls being indicated at 7 while the inclined bottom has been indicated at 8. The inner 85 side wall 9, in the structure shown in Figs. 1 to 4 inclusive, has inwardly directed vertical corrugations 10 so proportioned as to form snug seats for the outstanding corrugations 2 on the stove wall. The top portions of the walls 7 and 9 are flared outwardly or stepped, as shown at 11, so as to receive the depending stepped ribs 12 formed upon the bottom face of the top casting 13 of the reservoir. This top casting is preferably provided with lugs 14 adapted to be inserted into the openings 5 and an opening 15 may be formed in the top casting, this opening being normally closed by a removable lid or cover 16. Ribs 12 may 100 be secured to the stepped portion 11 of the reservoir in any suitable manner, the form of joint being such as to prevent overflow should the reservoir be filled up to the top casting 13. The bottom 8 of the reservoir 105 bears upon the bottom casting 17 which is provided with one or more depending arms 18, each of which has a slot 19 extending thereto from one side. One or more lugs 20 extend downwardly from the bottom 110 casting. In the structure illustrated, two arms 18 are to be used and two lugs 20 are

also to be employed but it is to be understood that, if desired, a single arm and a single lug may be used. The recessed and slotted lugs 6 receive heads 21 formed upon holding rods 22. One of these rods is provided for each arm 18 and an actuating head 23 is provided at the outer end of each rod and bears against arm 18. A lug 24 extends radially from each rod 22 and is so located that, when the reservoir is pressed tightly against the corrugated wall of the stove 1, lug 24 can be rotated, by means of rod 22 and head 23, so as to lap lug 20 and thus hold the reservoir in contact with the stove wall. With the parts thus positioned it will be apparent that water contained within the reservoir will be quickly heated by reason of the conduction of heat units from the corrugated wall of the stove through the corrugated wall of the reservoir contacting therewith. Should the water reach the boiling point and it should be desired to reduce or stop the boiling action, the rod or rods 22 can be rotated so as to release the lug or lugs 20 whereupon the lower end of the reservoir and its casing can be swung outwardly until the lug or lugs 24 are moved back to their initial position whereupon the reservoir can be released and lug or lugs 20 will move back by gravity against lugs 24, thus holding the reservoir in the position illustrated in Fig. 4. Thus an air space is provided between the corrugated walls of the stove and reservoir.

35 By removing the lid 16, water can be easily removed from or placed in the reservoir.

While in the structure shown in Figs. 1 to 4 inclusive, the corrugations on the stove wall extend outwardly and those on the reservoir wall extend inwardly, it is to be understood that this arrangement may be reversed, as shown in Fig. 6, wherein the stove corrugations are extended inwardly, as shown at 25 45 while the corrugations on the reservoir wall and which have been illustrated at 26, are projected outwardly. Furthermore, instead of employing rounded corrugations such as shown in Figs. 3 and 6, angular corrugations, one form of which has been shown at 50 27 in Fig. 7, may be provided.

It is preferred to arrange the sheet metal portion of the reservoir within a casing preferably formed of castings connecting the

top casting 13 to the bottom casting 17, these 55 castings, which have been designated generally at 28, being arranged along the front, back and outer sides of the sheet metal reservoir.

What is claimed is:—

1. The combination with a stove having a corrugated surface, of a reservoir having corrugations extended along straight lines upon one face and parallel with the corrugations of the stove, a housing in which the 65 reservoir is mounted, a depending projection upon the housing, and means adjustably supported by the housing and detachably engaging the stove for coöperating with said projection to hold the reservoir 70 either clamped against the corrugated portion of the stove or spaced from said portion.

2. The combination with a stove having a corrugated wall, of a housing detachably and tiltably connected at its upper end to 75 the stove, a reservoir seated in the housing and having an exposed wall formed with corrugations straight from end to end, and coöperating means upon the bottom of the housing and upon the stove for binding the 80 corrugated surface of the reservoir upon the corrugated portion of the stove and for holding the reservoir tilted away from said corrugated portion of the stove.

3. The combination with a housing a 85 stove having a corrugated surface, and means for connecting the housing to the stove, of a reservoir within the housing and having an exposed corrugated surface, the corrugations being extended along straight 90 lines and parallel with the corrugations on the stove, a sloped arm depending from the housing, a bracket upon the stove, a rod detachably engaging the arm and bracket and mounted for rotation, and coöperating 95 means upon the rod and housing for binding the corrugated surface of the reservoir against the corrugated portion of the stove and for holding said reservoir out of contact with the corrugated portion of the stove. 100

In testimony that I claim the foregoing as my own, I have hereto affixed my signature in the presence of two witnesses.

GEORGE G. GAREY.
